(57) **CLAIM**

The ornamental design for a floor lamp, as shown and described.

DESCRIPTION

FIG. 1 is a first perspective view of a floor lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the floor lamp thereof;

FIG. 10 is an enlarged view of the selected portion 10 in FIG. 1;

FIG. 11 is an enlarged view of the selected portion 11 in FIG. 1;

FIG. 12 is an enlarged view of the selected portion 12 in FIG. 2;

FIG. 13 is an enlarged view of the selected portion 13 in FIG. 5;

FIG. 14 is an enlarged view of the selected portion 14 in FIG. 5; and,

FIG. 15 is an enlarged view of the selected portion 15 in FIG. 5.

The broken lines represent the boundaries of the enlarged views and form no part of the claimed design.
